UNITED STATES PATENT OFFICE.

RENÉ EYBEN, OF NEW YORK, N. Y.

DESIGN FOR A BOTTLE.

61,409.

Specification for Design. Patented Aug. 29, 1922.

Application filed June 22, 1921. Serial No. 479,657. Term of patent 3½ years.

To all whom it may concern:

Be it known that I, RENÉ EYBEN, a citizen of Belgium, and residing in the city of New York, borough of Manhattan, in the county and State of New York, United States of America, have invented a new, original, and ornamental Design for a Bottle, of which the following is a specification, reference being had to the accompanying drawing, forming a part thereof, wherein—

Figure 1 represents a side view of a perfume bottle embodying my invention;

Figure 2 a top view of the same; and

Figure 3 a bottom view thereof.

My invention comprises broadly a di-

ametrical diminishing tri-lobular structure, two of the lobes forming the bottle portion thereof and being decorated by spaced vertical stripings, and the third forming the stopper being decorated by mottled encrustations in symmetrical form.

What I claim, and desire to secure by Letters Patent, is:

The ornamental design for a bottle substantially as shown and described.
